UNITED STATES PATENT OFFICE.

JACOB B. CAMPBELL, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,677, dated February 19, 1884.

Application filed January 9, 1884. Term of patent 3½ years.

To all whom it may concern:

Be it known that I, JACOB B. CAMPBELL, a resident of Yonkers, in the county of Westchester and State of New York, have invented and produced a new and original Design for a Carpet, of which the following is a full description, in connection with the accompanying photograph, which represents a face view of my new design for a carpet.

5 *This invention relates to a new ornamentation of the face of a carpet, oil-cloth, or analogous fabric.*

10 In the accompanying photograph are shown two bands, A B, into which the face of the carpet is divided. In the band A are rosettes 15 *a* and *b*. The ornamentation of the band B

consists of a novel grouping of the figures indicated in the photograph, of which *d* and *e* are conventional flowers, above which are the ornament *f* and the conventional flowers *g* 20 and *h* upon zigzag stems *i*.

I claim—

1. The design for a carpet, the same consisting of the bands A B and figures *a*, *b*, *d*, *e*, *f*, *g*, *h*, and *i*, substantially as shown. 25

2. The design for a carpet, the same consisting of the figures *d*, *e*, *f*, *g*, *h*, and *i*, substantially as shown.

JACOB B. CAMPBELL.
